[57] CLAIM

The ornamental design for a display rack design, as
shown and described.

DESCRIPTION

FIG. 1 is a front and left side perspective view of a
display rack showing our new design;
FIG. 2 is a rear elevational view thereof;
FIG. 3 is a top plan view thereof; and
FIG. 4 is a bottom plan view thereof.
The right side not shown is the same in appearance as
the rear view as shown in FIG. 2.

FIG. 1

FIG. 3

FIG. 2

FIG. 4
